DESIGN FOR A COMBINED VENDING AND DISPLAY STAND

James Leslie Wright, Hamilton, Ontario, Canada

Application March 25, 1936, Serial No. 61,775
In Canada February 21, 1936

Term of patent 7 years

To all whom it may concern:

Be it known that I, James Leslie Wright, residing at the city of Hamilton, in the county of Wentworth and Province of Ontario, Dominion of Canada, and a subject of the King of Great Britain, have invented a new, original, and ornamental Design for Combined Vending and Display Stands, of which the following is a specification, reference being had to the accompanying drawing, forming part thereof.

Fig. 1 is a perspective view of the combined vending and display stand, showing my new design, and

Fig. 2 is a top plan view thereof.

I claim:

The ornamental design for a combined vending and display stand, as shown.

JAMES LESLIE WRIGHT.
